(57) **CLAIM**

The ornamental design for a children's camera as shown and described.

DESCRIPTION

FIG. 1 is a top, front, left perspective view of a children's camera showing my new design;

FIG. 2 is a bottom, back, right perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the children's camera and form no part of the claimed design.
